Inventor:

William G. Algeo.

CO

United States Patent Office.

WILLIAM G. ALGEO, OF PITTSBURG, PENNSYLVANIA.

Design No. 2,860, dated January 28, 1868.

DESIGN FOR A COFFIN.

The Schedule referred to in these Letters Patent and making part of the same.

TO ALL WHOM IT MAY CONCERN:

Be it known that I, WILLIAM G. ALGEO, of the city of Pittsburgh, in the county of Allegheny, and State of Pennsylvania, have invented and produced a new Design for Coffins; and I do hereby declare the following to be a full, clear, and exact description thereof, reference being had to the accompanying drawing, making a part of this specification, in which—

Figure 1 is a perspective view of a coffin, which shows my improved design, and

Figure 2 is a longitudinal vertical section of the same.

Like letters of reference indicate like parts in each.

My improved design consists in the form and manner of ornamentation which I adopt in making the ends and top of a coffin.

That the character of my improved design may be more readily understood, I will proceed to explain the same.

The sides *a* of the coffin are made in the usual manner. On these rests a rim, *b*, which supports an ornamental moulding, *c*, of any well-known style, on which, in turn, is placed the raised cover *e*, with its lids *e'*.

The ends of the coffin, as well as of the rim *b*, mouldings *c*, cover *e*, and lids *e'*, I make of an octagonal shape, as at *d*; that is to say, the three faces *d*, at each end, are faces of an octagonal body of like shape. The mouldings *c* are united by bevel joints at both the sides and ends, to adapt them to the shape of the coffin. I thus make the ends and top of the coffin of a greatly-improved shape, and much more ornamental style.

What I claim as my invention, and desire to secure by Letters Patent, is—

The design for coffins herein set forth and described.

In testimony whereof, I, the said WILLIAM G. ALGEO, have hereunto set my hand.

WILLIAM G. ALGEO.
